UNITED STATES PATENT OFFICE.

JEAN I. EFFERENN, OF SPRINGFIELD, ILLINOIS.

MACHINE FOR SAWING FIRE-WOOD.

Specification of Letters Patent No. 11,417, dated August 1, 1854.

To all whom it may concern:

Be it known that I, JEAN I. EFFERENN, of Springfield, county of Sangamon, State of Illinois, have invented a new and Improved Machine for Sawing Wood; and I do hereby declare that the following is a full and exact description thereof, reference being had to the accompanying drawings and to the letters of reference marked 10 thereon.

The machine consists of a substantial saw-horse such as is commonly used by wood sawyers A A. Below the horizontal piece which connects the legs of the saw-horse 15 is supported the iron crank B B, to which is attached the two fly wheels C C. The arm D is attached to said crank consisting of two parts with teeth so that the same may be shortened or lengthened as circumstances may require. This arm acts horizontally and is connected with the vertical lever E E at the point F. The saw G is connected with the upper part of this lever which is fastened at its lower end to the 20 saw horse at the point H. By pulling on

the saw, the fly wheels, through the agency of the lever, arm, and crank, are set in motion and produce a regular and uniform motion, thereby enabling the operator to accomplish more work than can be effected by 30 the ordinary machine. The break I is used for the purpose of supporting the flywheels by a chain fastened to its upper extremity or for lowering the flywheels upon the ground so as to remove the whole machine 35 from place to place. In removing the machine the handles J J are used and are inserted into the saw horse at the points K K. The arm L is used to confine the wood to its place and hold it firm. 40

What I claim as my invention and desire to secure by Letters Patent is—

The combination of a saw and saw-horse with fly-wheels as above described through the agency of a lever E, arm D, and crank B. 45

JEAN I. EFFERENN.
